UNITED STATES PATENT OFFICE

SUMTER B. BATTEY, OF NEW YORK, N. Y.

REPEATING MECHANISM FOR TALKING MACHINES

Application filed August 21, 1922. Serial No. 583,132.

This invention relates to repeating mechanisms for talking machines of the type set forth in United States Patent No. 1,629,986, granted May 24, 1927, to me and Bryan M.

5 Battey jointly, the object of the present invention being to provide an improved mechanism of this type. The device referred to comprises a mechanism carried at or near the sound box in which a wheel or similar 10 device is provided which is normally held above the record until the end of the sound groove is reached, whereupon it is moved into contact with the record, thus elevating the sound box. The continued rotary movement 15 of the record causes the wheel to move laterally outward to the edge of the record, whereupon it works over the same, thus lowering the sound box until the needle moves into contact with the sound groove at the 20 beginning of the latter. While such construction was an improvement on the art theretofore existing, I have found in practice that its operation can be considerably improved in several respects, notably by providing a wheel or the like which is elongated and preferably tapered, whereby the sound box and needle can be restored to contact with the record so gently that there is no liability of injury either to the record or 25 needle. The device of the present invention includes certain other features and improvements which will be hereinafter more fully described.

30 In the drawings which illustrated the preferred form of the invention:

Figure 1 is an elevation looking toward the edge of the sound box, and showing also the record and turntable, the parts being illustrated as approaching the position in which 40 the repeating mechanism is to work.

Fig. 2 is an elevation at right angles to Figure 1.

Fig. 3 is a similar view showing the position of the parts after the needle has been elevated.

Fig. 4, Fig. 5, and Fig. 6 are sectional views of details.

Fig. 7 is an under-side view of Figure 1.

Fig. 8 is a view of the device as applied to a different type of phonograph arm.

Fig. 9 is an elevation of the preferred form of the invention.

Fig. 10 is a view at right angles to Fig. 9.

Fig. 11 is a detailed view in section.

Referring first to Figs. 1-8 of the drawings let A indicate the usual phonographic turn-table, B the record having the usual aperture fitting over the central stud C. D is the sound box carried on a curved arm E capable of being tilted around the axis F in Figures 1 and 7, whereby to raise or lower the sound box.

The repeating mechanism is fastened to the arm E by a strap or band G, which is tightened about the arm by a thumb screw H 55 screwing on a threaded bolt I. Between the two is located the block J which is capable of rotating between the ends of the band G, but which is held in frictional contact with the two so that when rotated it will hold its adjusted position. Affixed to the under-side of the block J is an arm K extending toward the sound box, which arm serves to support at its free end the shaft L of the roller M. The shaft L is not mounted directly upon the arm K, but is mounted in a block N which has a pivoted connection with a swinging member O which is pivoted at P to the arm K so that the member O is capable of moving in a horizontal plane and thus adjusting the 70 degree of angularity of the shaft L. Preferably, the swinging member O has means for holding it in its adjusted position, this being effected in the present construction by a frictional arm P' which engages the under- 75 side of the arm K. The block N is hinged or pivoted on an axis N¹ to the swinging member O, as is best seen in Figs. 1 and 6. The swinging member O may conveniently carry hinge ears N² which freely embrace the pivot 80 or hinge pin N¹ between corresponding ears N⁴ formed at the end of member O, the said latter ears rigidly gripping the pin and holding it against axial or angular displacement relative to member O. A spring N² normally holds the tilting block N (as well as the shaft L and roller M) in its uppermost position. The effect of this construction is that the roller M is capable of three movements. The first of these is caused by tilting the 85

90

95

100

block J around the axis I, the effect of which is to tilt the shaft L upwardly or downwardly so as to adjust the lower part of the periphery of the roller so that it makes proper contact with the record for different shapes and sizes of sound box, and different degrees of projection of the needle. The second adjustment is of the swinging member O around the axis P which determines the angularity 5 of the shaft L so that the sound box may be moved at a slower or faster speed across the face of the record when the sound box is being restored to its initial or outer position with regard to the record. The third movement 10 of the shaft L is around the pivot N¹, and this movement is availed of to bring the roller M into contact with the record, whereby to lift the sound box when it reaches its innermost position in a manner to be described. 15

While the frictional contact between the block J and the ends of the strap G might be relied upon to hold the arm K in its various tilted positions, I prefer to provide a more 20 secure means for effecting this result. Referring especially to Figs. 2 and 7 it will be seen that the block J is provided with a side extension Q having a slot Q' in which fits the reduced neck Q² of an adjusting screw Q³. 25 The latter screws into a part R held in place by the bolt I, or otherwise prevented from turning. It will be seen that when the screw Q³ is turned to the right, the block J will be moved around its pivotal axis, thereby turning 30 the arm K around its longitudinal axis to lower the roller. The reverse movement raises it. These adjusting movements do not interfere with the up and down swinging movement of the roller which is relied upon 35 to raise the sound box to lift the needle from the record. 40

In order to better support the sound box when it is elevated, I prefer to provide a 45 spring S which is preferably bent on itself and which is fastened to arm K, its free end contacting with the sound box as shown at S'. If desired, an adjusting screw such as S² can be utilized to throw the end of the spring further upward, or permit it to move further 50 downward to suit different types of sound boxes. Preferably, the end S³ of the spring is carried forwardly so as to constitute a stop for the block N as it swings downwardly, thus limiting the actuating movement of the roller 55 so that it does not move sufficiently far to again lower the sound box after it has raised the latter.

The roller is preferably actuated to raise the sound box by a mechanism which is similar to that shown in the aforesaid application, 60 namely, a pair of knife edges, one of which, T, is carried adjustably in a block T' frictionally held by the central stud C of the turn-table A, and the other of which, U is carried by the tilting block N. The effect of 65

these knife edges is that when the needle arrives near the end of the sound groove, the knife edges are brought into contact. This contact causes the knife U to ride up over the top of the knife T, thus swinging the shaft L and roller M from the inoperative position shown in Fig. 2 to the operative position shown in Fig. 3, thereby lifting the sound box so that the needle is disengaged. 70

An important feature of the invention is the construction and operation of the roller M or its equivalent. In prior structures, a member has been provided, the periphery or working face of which is narrow, with a result that as it passes off the edge of the record it is apt to drop the sound box, thus injuring the record or destroying the needle. In the aforesaid application, the descent of the sound box is less abrupt, but can, nevertheless, be improved upon. 75

According to the present invention, I provide a member with a broad working face which preferably does not pass entirely off the record, but which lowers the needle gradually into gentle contact with the record. Whatever type of member is employed, whether of the wheel or other type, it should have a broad working surface which is inclined with reference to the plane of the record; that is to say, its outer edge should be nearer the record than its inner edge. The result of this construction is that as the record rotates, the sound box will be gradually lowered as the wheel, or its equivalent, works further off the edge. This result could be accomplished by the use of any inclined plane having an extended surface in a direction which is radial to the record, but I prefer to use a rotatable member such as the roller M, since by using such a member there is less friction on the record as the member moves across the face thereof. However, the most effective and simple device for accomplishing the purpose is a tapered roller such as is illustrated, of which the periphery is of less diameter on its inner side than on its outer. The periphery need not be flat such as is illustrated in Figs. 1 to 7; it may be curved in either direction, an example of a concave roller being shown in Fig. 8. 100

I prefer to form the roller of rubber, and, in order that it may rotate freely, I provide a bushing M' of metal or other suitable material. The shaft L is best threaded as illustrated in Figure 1, and a screw threaded collar V is provided for adjusting the position of the roller. The latter may be carried loose upon the shaft, since in operation its movement tends to throw it outwardly against the adjusting collar V. 110

In applying the device to a phonograph, clamp G is passed around the tubular arm E, and screwed tight by the adjusting nut H. A needle is then inserted in the needle carrier, and the adjusting nut Q³ is manipulated until 120

the roller is in proper position vertically to effectually lift the sound box. The swinging member O is then adjusted horizontally until the shaft L has the correct angularity to cause the sound box to travel over the record at the proper rate of speed, and for a sufficient distance to carry the roller to the edge of record.

In operation, the knife edge T is set at the proper point for the individual record; the roller is normally held in its inoperative position by the spring N² until the last sound groove is reached by the needle, whereupon the knife edges T and U contact, thus lowering the roller so that it contacts with the record and lifts the sound box. The sound box is then moved across the face of the record by the action of the latter upon the roller, and when the roller reaches the edge of the record and assumes a position similar to that shown in dotted lines in Figure 1, the sound box will be gently lowered with its needle into contact with the first record groove. As soon as the weight of the sound box is removed from the roller, its spring N² restores the roller with its shaft L to the inoperative position shown in Fig. 2.

In Fig. 8, I have shown the device as applied to a phonograph having a straight tone arm. In this construction, the arm K' extends at an angle to the axis of the block J' so that by adjustment of the thumb screw Q⁴, the shaft L' is raised and lowered. In Fig. 8, the construction results in a bodily movement of the shaft instead of a tilting movement as in Figs. 1 to 7, but the effect of raising and lowering the roller remains the same. In other respects, the two mechanisms are substantially identical.

Referring to the preferred form of the invention which is illustrated in Figs. 9 to 11, G³ is a clamp by which the device is attached to the sound box, clamping screw G⁴ being provided to engage the sound box near its periphery. The clamp G³ is formed with an arm G⁵. The arm K³ is pivoted at K⁴ to the clamp, and an adjusting screw K⁵ is provided which fits in a slot formed in the upper end K⁶ of the arm K³, and is threaded into the arm G⁵ so that arm K³ may be tilted upwardly or downwardly for adjusting the position of the roller M³. The latter is carried on a shaft L³ as before, which is mounted on a member O³ pivoted to the arm K³, by a pin N⁴, a spring N³ being provided which normally tends to raise the roller M³. The knife edge U⁴ is similar to that shown in Figs. 1 to 7, as is also the stop S⁴ which is adapted to limit the movement of the part O³ around the pivot pin N⁴. The part O³ is pivoted to a plate P³ which is capable of an angular movement around the screw P⁴ by which movement angular adjustments of the roller with relation to the record are secured.

I have found that the roller M, or its equivalent, makes a very effective friction stop

for the record and machine if it is secured against rotation. I prefer to make the roller yieldingly held, and to this end introduce a spring W⁴ between the end of the roller and the part O³. This spring bears against a bushing W⁵, and when the thumb nut V is screwed up tightly, the roller is clamped sufficiently so that when the knife edge engages the part T, and the roller is dropped, it will rotate slightly so as to bring the parts to rest without shock and without undue wear upon the roller. However, the roller will not under such circumstances have sufficient capacity for rotation to travel across the face of the record.

While I have shown and described one form of the invention, it will be understood that I do not wish to be limited thereto since various changes may be made therein without departing from the spirit of the invention.

What I claim is:

1. A repeating mechanism for talking machines having a movable sound box or the like, said mechanism including a member independent of the needle adapted to be engaged with the record, said member cooperating with the record to move the sound box in a direction toward the beginning of the sound record and also to lower the sound box whereby to bring said needle into engagement with the record, said member presenting to the record an inclined surface which is of considerable breadth in a direction radially of the record, and which surface is inclined from the horizontal so that with respect to the record, a radially inward point on said surface is higher than a radially outward point thereon.

2. A repeating mechanism for talking machines having a movable sound box or the like, said mechanism including a member independent of the needle adapted to be engaged with the record, said member cooperating with the record to lower the sound box whereby to bring said needle into engagement with the record, said member comprising a roller and a shaft therefor, the roller having a broad face radially of the record, and said parts being constructed and mounted so that the lower face of the roller is inclined upwardly toward the interior of the record and in a vertical plane passing through the axis of said roller.

3. A repeating mechanism for talking machines having a movable sound box or the like, said mechanism including a member independent of the needle adapted to be engaged with the record, said member cooperating with the record to lower the sound box whereby to bring said needle into engagement with the record, such member comprising a roller having a broad face radially of the record, and said roller being tapered on its periphery.

4. A repeating mechanism for talking

machines having a movable sound box, said mechanism including a member independent of the needle adapted to be engaged with the record, said member co-operating with the record to move the sound box in a direction toward the beginning of the sound record and also co-operating therewith to lower the sound box, a shaft for said member, and means for raising and lowering said member by moving said shaft, said means comprising a tiltable block rigidly attached to said shaft and means for tilting said block.

5. A repeating mechanism for talking machines having a movable sound box, said mechanism including a member independent of the needle adapted to be engaged with the record, said member co-operating with the record to move the sound box in a direction toward the beginning of the sound record, means for adjusting the angularity of said member in a horizontal plane, and means for permanently adjusting its vertical position.

6. A repeating mechanism for talking machines having a movable sound box, said mechanism including a member independent of the needle adapted to be engaged with the record, said member co-operating with the record to move the sound box in a direction toward the beginning of the sound record, means for mounting said member to swing upwardly and downwardly, means for adjusting said member vertically, and means for varying the angularity of said member.

7. A repeating mechanism for talking machines having a movable sound box, said mechanism including a member independent of the needle adapted to be engaged with the record, said member co-operating with the record to move the sound box in a direction toward the beginning of the sound record, said means comprising a roller, a shaft for said roller, means whereby said shaft can be moved bodily to bring said roller into and out of contact with the record, said last named means being pivoted for adjustment in a horizontal plane, and means for permanently adjusting the roller vertically.

8. A repeating mechanism for talking machines, said mechanism including a roller adapted to travel over the face of the record, a shaft for said roller, a tiltable member adapted to permit the swinging of the roller into and out of contact with the record, a swinging member upon which said tiltable member is pivoted and adapted for adjustment angularly of the record in a horizontal plane, and an adjustable arm to which said swinging member is connected, said arm being pivotally supported by the tone arm structure of the phonograph.

9. A repeating mechanism for talking machines having a movable sound box or the like, said mechanism comprising a roller adapted to move across the face of the record, means for mounting the roller whereby it

may swing upwardly and downwardly into and out of contact with the record, an arm carrying said roller, mounting means and means for adjustably connecting said arm to the sound box of the phonograph comprising a clamp adapted to embrace the sound box upon which said arm is pivoted, and an adjusting screw to vary the position of said arm with respect to said clamp.

10. A combined stop and repeat mechanism for talking machines, said mechanism including a roller adapted to be engaged with the record, said roller co-operating with the record to move the sound box in a direction toward the beginning of the sound record, and frictional braking means for said roller adapted to check the rotation of the roller, whereby to stop the rotation of the record after said braking means becomes operative.

In witness whereof, I have hereunto signed my name.

SUMTER B. BATTEY.
